UNITED STATES PATENT OFFICE

ETIENNE DANGER, OF PARIS, FRANCE, ASSIGNOR TO SOCIETE USINES DECOUFFLE, OF PARIS, FRANCE

CUTTING DEVICE FOR CIGARETTE MACHINES

Application filed January 9, 1930, Serial No. 419,638, and in France January 15, 1929.

The present invention has for object a device applicable to machines which manufacture cigarettes in the form of a continuous rod, and serving to cut the cigarette rod in sections of the required length in proportion as it is produced.

For obtaining a cut which is perfectly at right angles to the cigarette rod and not hindering the continuous advance of the latter, it is necessary that the cutter, as well as the support containing the cigarette rod at the place where the cut is to be made, participate, during the cutting operation, to the continuous movement of the cigarette rod.

15 The invention has for object to obtain an improved cutting device, capable of operating at a very high speed.

The apparatus belongs to the type in which the cutter receives:

20 1. From a first mechanism, a uniform movement of rotation about the axis parallel to the cigarette rod.

25 2. From a second mechanism, a periodical oscillatory movement parallel to the cigarette rod.

With the known apparatus belonging to this type, the speed of the cigarette machine is limited to a small value, owing to the vibrations created in the machine by the forces 30 of inertia due to this last periodical oscillatory movement.

Owing to the arrangements adopted in the apparatus forming the subject-matter of the present invention, the masses subjected to the above mentioned reciprocating movement are reduced to such an extent that even at the very high speeds necessitated by modern machines having a very great output, the vibrations to which the machine is subjected 40 owing to the forces of inertia generated by these masses are practically imperceptible.

In accordance with the invention, the cutter shaft carries a support on which the cutter-carrier is pivoted, the pivoting axis and 45 the cutter being arranged on either side of the shaft, whilst a point of this cutter-carrier located between the shaft and the cutter is connected by a small link to a guide device serving to produce the to-and-fro movement 50 of the cutter.

The movements of the cutter are obtained in the following manner:

Movement of rotation imparted to the axis of oscillation by a plate receiving a uniform circular movement, thus driving the cutter-carrier. 55

Oscillatory movement, by rendering a small link rigid with the rocking lever, the other end of this link being compelled to remain in a fixed plane inclined on the axis of 60 the cigarette rod.

The accompanying drawing illustrates a form of construction of the device in accordance with the invention.

Fig. 1 is a longitudinal section.

Fig. 2 is a cross section made according to line 2—2 of Fig. 1.

On a cutter shaft 1, receiving a continuous rotary movement transmitted thereto by the driving shaft, is pinned a structure forming 70 a support 2 on which is pivoted, at 3, the cutter-carrier 4.

The cutter receives, in addition to the rotary movement imparted thereto by the shaft 1, an oscillatory movement about the axis 3, 75 the direction of the latter being orthogonal relatively to that of this shaft.

A small link 5 is pivotally connected, at one end, to the cutter-carrier, and its other end forms a spherical member 6 movable in a corresponding recess or housing of the outer movable part 7 of a ball bearing, the inner 80 fixed part 8 of which is integral with a bowl 9 surrounding the shaft 1 and capable of being more or less inclined relatively to this 85 shaft.

The bowl 9 is provided for that purpose with an arm 10 in which is formed a slot 11 receiving a screw 12 allowing to adjust the inclination; this arm is provided with a graduation 13, divided in units of length of cigarettes, so as to avoid fumbling. 90

The bowl 9 is sectioned at 14 so as not to hinder the displacements of the cutter-carrier.

During each revolution of the latter, the ring 7 of the ball bearing, driven by the link 5 effects also a revolution, and as said ring is obliquely held, the cutter-carrier is compelled to rock or oscillate about its pivoting axis 3. 95

As it is easy to regulate the speed of trans- 100

lation of the cutter and of the cutter guides in concordance with that of the cigarette rod, it results from the combination of the movements obtained that, during the cutting, the relative displacement of the cutter relatively to the cigarette rod can be considered as strictly perpendicular to the latter.

It is to be understood that the number, the shape, the arrangement and the assemblage of the various parts can be modified in any suitable manner without departing from the scope of the invention.

The ball bearing can be replaced by a double abutment, or by any other combination allowing to obtain the movement described.

15 Claim:

20 In a cutter device for cigarette machines forming a cigarette rod receiving a continuous movement, the combination of a cutter shaft receiving a rotary movement, a support mounted on this shaft and rotating with the same, a cutter-carrier pivoted on the said support on one side of the said shaft, a cutter secured on the said support on the opposite side of the shaft, a small link pivoted 25 on the cutter-carrier at a point located between the said shaft and the cutter, and means for producing a to-and-fro movement of the said link and of the said cutter.

30 In testimony whereof I have hereunto affixed my signature.

ETIENNE DANGER.
